(57) **CLAIM**

The ornamental design for a charger, as shown and described.

DESCRIPTION

FIG. 1 is a bottom, front, right side perspective view of a charger, showing my new design in a first configuration; FIG. 2 is a top, rear, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a top, rear, left side perspective view of the charger of FIG. 1, shown in a second configuration. The broken lines in the figures depict portions of the charger that form no part of the claimed design.
